UNITED STATES PATENT OFFICE.

JAMES M. SCURR, OF CRESTON, IOWA.

FASTENER.

SPECIFICATION forming part of Letters Patent No. 579,899, dated March 30, 1897.

Application filed April 6, 1896. Serial No. 586,302. (No model.)

To all whom it may concern:

Be it known that I, JAMES M. SCURR, a citizen of the United States, residing at Creston, in the county of Union and State of Iowa, have 5 invented a certain new and useful Improved Fastener, of which the following is a specification.

My invention relates to certain improvements in means whereby the end of a strap, line, or other like object is detachably secured to some other object.

The object of my invention is to provide a fastener for the end of a line, strap, or other like object which shall be simple and cheap 15 in point of construction, which shall be positive and secure in attachment, and which shall permit of convenient and ready detachment.

My object, further, is to provide means 20 whereby the strain of the pull is distributed in the most desirable manner.

My invention has certain other objects in view; and it consists in certain features about 25 to be described, and pointed out in my claims, reference being now had to the accompanying drawings, in which—

Figure 1 is a perspective view showing the fastener securing the strap to an object. Fig. 2 is a like view showing the strap in the position 30 assumed when being detached. Fig. 3 is a side view of the fastener, showing it securing the strap to an object. Fig. 4 is a perspective view of a modified form. Figs. 5 and 6 are like views showing two positions assumed by the strap as the same is being adjusted to the fastener for securing the strap to an object. Fig. 7 is a plan view of the fastener, showing the strap secured to an object and adjusted in the fastener. Fig. 8 is 35 a side view of the same.

Referring to Figs. 1, 2, and 3, my invention consists in a fastener which is secured rigidly to the strap or other like object and held permanently thereon, which fastener is 45 composed of a bottom guide-plate A and an upper or top guide-plate B, held together in parallelism by means of the web D, the bottom guide-plate A, the top guide-plate B, and the web D all being made in one piece. As

50 these parts are constructed, a guiding member E is provided having an open longitudinal side G, which member is mounted upon

and secured to the strap H by means of rivets or otherwise through the bottom guide-plate A. The guiding member E is secured to the 55 strap at or near one end thereof, and also secured to said strap in proximity to the guiding member E is a holding-clip J, which is adapted to be brought into engagement with or separated from the guiding member 60 E by a longitudinal pull of the strap. This clip J is provided with an upturned engaging lip J², which when the parts are in the position shown in Fig. 1 fits into a recess cut out of the edge of the member E. The clip is of 65 the construction shown in Fig. 2, having a flange on each side.

Referring to Fig. 2, the preliminary adjustment of the strap for fastening to the ring K will be observed. One end of the strap having been inserted through the ring it is then inserted sidewise in the longitudinal opening G, and as a pull is exerted longitudinally upon the strap it is brought lengthwise into and between the top and bottom guiding- 75 plates A and B. In the continued further pull upon the strap the holding-clip J is brought into engagement with the guiding member E', as shown in Fig. 1, the strap sliding lengthwise through the guiding-plates 80 A and B. When the holding-clip J is positioned and the strap pulled taut about the ring, the upturned lip J² of the engaging clip J engages the recess in the guiding member E and withholds the strap from lateral displacement.

Projected forwardly from and formed integrally with the bottom guide-plate D is a strain-receiving extension H², which is slightly bent downward, and about the outer end edge 90 of which the strap is turned.

By reference to Fig. 3 more particularly it will be observed that the strain of the pull of the strap is imposed upon the said end edge of the extension H² and also upon the 95 object to which the strap is secured, in this instance the ring K. It is further evident that the function of this strain-receiving extension H² is to relieve the guiding-plates A and B from any stress which would tend to 100 distort these parts.

In order to release the strap from its fastened position, it is only necessary to push the strap forwardly, so that the lip J² is dis-

engaged from the edge of the member E, and then by a lateral movement pass the strap out through the longitudinal opening G.

Referring now to the modified form shown 5 in Figs. 4 to 8, inclusive, I provide a bottom guide-plate A², which is secured to the strap II by means of rivets or in any other suitable manner. Formed integrally with the bottom guide-plate are the engaging lips B² and B³, which extend over in parallelism with the bottom plate and from each side of said plate, being held in this position by means of the webs D² and D³. I thus provide the openings G² and G³ between said lips and the bottom 15 guide-plate, which openings are on either side of said plate. In this form also I provide the forwardly and downwardly extended strain-receiving member II², as in the form previously described.

20 In order to secure the strap by the fastener, the end thereof is passed through the ring L and a portion of its length inserted in the opening G¹ between the two lips B² and B³, which opening extends diagonally across the 25 bottom guide-plate A², this opening G¹ being formed diagonal by means of the formation of the inner edges of the said lips B² and B³. When the strap has thus been positioned, as shown in Fig. 5, by exerting a pull thereon 30 the strap is brought into the position as shown in Fig. 6, and by a further continued pull it is then brought into the position shown in Figs. 7 and 8, thus securely holding the strap to the object and within the fastener. In this 35 form of my device it is evident that the strain is imposed about the end edge of the strain-receiving member II² and the ring L, as in the form previously described.

In order to release the fastening, it is simply necessary to move the strap laterally, 40 whereby it passes out from beneath the lips B² and B³ into the diagonal opening G¹ and then drawn out of this opening.

Having thus described my invention, what 45 I claim as new therein, and desire to secure by Letters Patent, is—

1. In combination with a strap, a base-plate secured to the end thereof, a parallel top plate supported from the base-plate at one side and 50 providing a channel or recess to admit of the

turned-back or looped portion of the strap being inserted laterally into said channel and then moved longitudinally to contact the loop and means for retaining the turned-back portion against lateral displacement in said 55 channel until it has first been moved longitudinally to enlarge the loop, substantially as described.

2. In combination with a strap, a base-plate secured to the end thereof and having an angular extension forming a strain member, a parallel top plate carried by said base-plate at one side and forming a lateral channel or chamber to admit of the turned-back or looped portion of the strap being inserted laterally 60 therein and then moved longitudinally to contract the loop, and means for preventing the lateral displacement of the strap until it has first been moved longitudinally to enlarge the loop, substantially as described. 70

3. In combination with a strap, a base-plate secured to the end thereof, a parallel top plate carried by said base-plate at one side and providing a channel to admit of the turned-back or looped portion of the strap, being inserted 75 laterally therein and then moved longitudinally to contract the loop, and means carried by said strap for engaging one of the plates on such longitudinal movement whereby the strap is retained against lateral movement in 80 the channel while the loop is contracted, substantially as described.

4. In combination with a strap, a base-plate secured thereto, a parallel top plate carried by said base-plate at one side and providing 85 a channel to admit of the looped portion of the strap being inserted laterally therein and then moved longitudinally to contract the loop, and a retaining device carried by said strap and operating on the longitudinal movement of 90 the strap in said channel to engage a notch in one of said plates and retain the strap against lateral displacement, substantially as described.

In testimony whereof I affix my signature 95 in presence of two witnesses.

JAMES M. SCURR.
